UNITED STATES PATENT OFFICE.

HENRY H. CUMMINGS, OF NEWTON, MASSACHUSETTS, ASSIGNOR TO
ADAMS D. CLAFLIN, OF NEWTON, MASSACHUSETTS.

TICKET-DELIVERING MACHINE.

No. 839,457.

Specification of Letters Patent.

Patented Dec. 25, 1906.

Application filed November 15, 1905. Serial No. 287,438.

To all whom it may concern:

Be it known that I, HENRY H. CUMMINGS, a citizen of the United States, and a resident of Newton, in the county of Middlesex and 5 State of Massachusetts, have invented new and useful Improvements in Ticket-Delivering Machines, of which the following is a specification.

My invention relates to coin-controlled 10 ticket marking, delivering, and severing devices; and it consists in sundry mechanical improvements by the aid of which the marking of a ticket-strip is effectuated in part by the insertion of a proper coin into the mechanism and in part by the operation of a train 15 of mechanical devices which is unlocked by the insertion of the coin and wherein the marking, delivery, and severing of the ticket are accomplished in a stated cycle which can- 20 not be repeated until a subsequent coin is introduced into the mechanism.

The particular and especial purpose for 25 which my invention and improvements are designed and adapted is to furnish the operators of railway-cars or other public conveyances with an efficient, convenient, and reliable mechanical safeguard against the fraudulent use by employees of transfer-slips which are at the present time so gen- 30 erally used. Other analogous situations may be imagined or may arise which call for analogous protective measures, and in such cases the utility of these inventions and improvements may be extended beyond the 35 specific instances mentioned.

The apparatus as a whole comprises ticket printing and delivering devices which will be 40 found desirable if not practically necessary for the purposes to which this mechanism is addressed. These devices are therefore de- 45 scribed herein, although they are reserved for claim in an application concurrently pending herewith filed by me, which is a division of this application.

45 In the drawings hereto annexed, Figure 1 is a front elevation of the casing of my ticket marking and delivering mechanism, showing the operating-handle and the coin-apertures. Fig. 2 is a view of the same with one of its 50 covers removed. Fig. 3 is a section taken on the line 3 3 of Fig. 2. Fig. 4 is a view of the rear of the device with the cover removed from the casing. Fig. 5 is a section along the line 5 5 of Fig. 3. Fig. 6 illustrates one of

the tickets after it has been marked and sev- 55 ered from the strip, the time-stamp impres- sion upon said ticket not being shown in this figure. Fig. 7 is a view of the interior of the casing, showing the side of the timepiece- compartment, the slot wherethrough the 60 ticket-slip emerges, and the time-stamp dial and other stamping-type which may be supplied, if desired. Fig. 8 is a view of the strip-holder and strip-severing devices shown removed from the casing. Fig. 9 is an eleva- 65 tion, on an enlarged scale, of the main operating-shaft of the machine; and Fig. 10 is a sectional view from below, on a similar enlarged scale, along the line 10 10, Fig. 2, showing the 70 inside of the upper and curved portion of the strip-holder.

The ticket marking and delivering mech- 75 anism is inclosed in a metallic case or box H, Fig. 1, provided with sliding covers, as H', which may be locked in position. For con- 80 venience the casing may be supplied externally with clips or links (not shown) whereby to suspend it around the neck of the railway-car conductor or other official. In the front cover H', I provide a number of parallel slots H³, each of which is of the proper size to admit of the passage of a coin—say a five-cent piece—and alongside of the slots H³, I provide also a series of slots H⁴, through 85 which may be displayed to view a tablet which rests just under the cover H' and on which may be printed, as shown, the appropriate names or abbreviations thereof of as many streets or routes as may be provided for by transfers to be issued by the railway- 90 conductor carrying this ticket stamping, marking, and delivering device. The han- 95 dle H⁵ is pivoted to swing externally over the sliding cover H', carrying the shaft K, and is provided with a segmental slot h⁵, through which projects the driving-pin k of the shaft K, this slot permitting the handle H⁵ to be swung freely back and forth through the angular distance subtended by the slot h⁵. The normal position of the handle H⁵ is in- 100 dicated by the dotted lines in Fig. 1, and when in this position the handle serves as a shield or cover for the multiple coin-aper- ture H³. When it is desired to insert a coin into any of the coin-passages in the said mul- 105 tiple aperture, the handle H⁵ can be swung to one side, as shown in Fig. 1. A cut-away portion of the cover H' is filled by the plate

H^2 , so that the cover H' may be slid outward under the handle H^5 and past the shaft K . Referring to Fig. 5, it will be seen that inside the casing H , I provide a compartment or receptacle E , in which is laid the ticket-strip E' , the same being folded back and forth upon itself, so that a considerable length of strip may be laid compactly in a small space. A light spring e' holds the folded strip E' in proper position. The end of this strip is led upward and through the strip-holder D , under the thin sheet-metal cover d^4 , and down the substantially vertical portion d^3 of the strip-holder to a point near the cutting mechanism F . At regular intervals along the strip E' perforations E^3 are made. (See Fig. 6.) Each measured space on the ticket-strip E' is printed with the matter appropriate to the situation, the transfer destinations being printed in a column to correspond with the column of coin-apertures H^3 .

Preliminary marking of the ticket-strip.—Directly beneath the coin-apertures H^3 there is placed a semicylindrical coin-receptacle B , Figs. 2 and 3, and at one side of this coin-receptacle (to the right thereof as viewed in Fig. 2) appear the series of ticket markers or perforators A , whereof the perforating or marking points a' lie in the apertures a^2 in the strip-holder D , the wipers a^4 standing in the path of one edge of the inserted coin and the standards a^5 being pivoted to a rod a^6 and provided with feet a^7 , against which press the leaves a^8 of the spring secured to the base of the coin-receptacle B by screws, as a^9 . When a passenger on handing his fare to the conductor says, for instance, that he wishes a transfer to Moody and Main streets, the conductor slips a five-cent piece into the slot H^3 , which stands abreast of the words "Moody-Main," which show through one of the slots H^4 , as illustrated in Figs. 1 and 2. This act of insertion of the coin causes one edge of the coin to press against the wiper a^4 and to thrust the marker A sideways, so that the marking-point a' passes into the aperture a^2 and makes a mark or perforation in the ticket-strip, which after the ticket has been removed and severed in the manner to be described will show somewhat as the mark e' in Fig. 6.

Release of the stamping and feeding mechanism.—As the coin inserted in one of the slots H^3 is further pressed into the coin-receptacle B it must pass into and through one of the notches c' in the rocker-plate C , and to accomplish this the rocker-plate C will rock to the left, as shown in Fig. 3, the other side of the coin pressing upon the edge b' of the receptacle B as an abutment. The rocker C is provided with a wiper c^2 and with arms c^3 and pivot-pin c^4 and a spring c^5 , which normally urges the rocker-plate C to the position shown in Figs. 2 and 3. When the rocker-plate C is in this normal position,

the latch c^6 , Fig. 2, is held upward by the spring c^8 (secured by the screw c^9) into the path of the segmental disk k' , so that the shaft K , to which the segmental disk e' is secured, may not rotate. The rotation of the shaft K in the opposite direction is controlled and restrained by the pawl r , which is controlled by the spring r' , this pawl r working in the ratchet-wheel k^2 . When the rocker-plate C is moved by the insertion of a coin, the wiper c^2 thereon presses against the tail of the latch c^6 , depressing the outer end of the same against the stress of the spring c^8 , thus releasing the shaft K and allowing the segmental disk k' to turn as the handle H^5 is rotated clockwise, Fig. 1.

Successive operations of the main shaft.—The first office performed by the rotating shaft K is the release of the coin from the grip of the rocker-plate C . This rocker-plate is provided with a finger c^7 , Figs. 2 and 5, which stands in the path of the segmental disk k' , and as this disk is rotated it presses against the said finger and thrusts the rocker-plate C still further from its normal position, freeing the coin, which then drops from the cylindrical receptacle B into the lower compartment of the casing H . The next succeeding function of the rotating shaft K is to release the ticket-stamping mechanism. A detent p is pivotally hung in the path of the pin k^7 , which is carried by the shaft K , Figs. 2 and 9, and the other end p' of this detent engages the downwardly-curved end of the strip-carrier D , so that the latter is unable to move toward the stamping-types. The strip-carrier D is held normally in this locked position by the spring D^2 . (Shown in Fig. 4.) When the pin k^7 lifts the detent p and removes the catch p' at its end from engagement with the strip-carrier D , this carrier is then free to turn upon its pivot d' . The rotating shaft K next throws the strip-carrier D into pressure contact with the types $L L' L^2$ (shown in Fig. 7) and performs this operation by means of the coaction of the wiper-roller k^4 , carried by the lug k^3 , with the cam-block D' , which is secured on the inside of the strip-carrier D . This coaction forces the carrier D into contact with the types and the strip b , lying in the carrier D , is properly impressed. The cover d^4 of the carrier is cut away to form a suitable opening, as at L^3 , Fig. 8, through which the types operate, the yielding pad e^2 , over which the strip passes, providing a proper surface to permit the action of the types. The ticket-strip having been indented by the types $L L' L^2$, the roll k^4 passes by the cam-block D' , the spring D^2 returns the strip-carrier D to its normal position, and the roll k^4 next makes contact with the arm f^{10} of the bell-crank lever, whose other arm f^9 is connected to the hanging link f^8 , which in turn connects with the lever f^7 , which is pivoted upon the pin d' , which serves also for

the pivot for the strip-carrier D. A spring f¹¹, Figs. 4 and 5, resists the movement of the bell-crank f¹⁰ f⁹ and would return the bell-crank lever to its normal position after the 5 passage of the roll k⁴ were it not for the catch f⁴, which, pivoted at f⁵ and controlled by the spring f¹⁷, (see Fig. 4,) automatically opposes its notched end f⁶ over the top of the cutter F, which is depressed by the lever f⁷, 10 which projects into the aperture f² of the cutter-plate, this plate being mounted to slide upon the back plate F', (being secured thereto in this sliding relation by the screws f³, which play in slots cut in said cutter-plate F, the 15 cutting edge f' thereof being shown clearly in Fig. 8.) Thus by the catch f⁴ the cutter-plate F is held against the stress of the spring f¹¹. After accomplishing the setting of the cutter-plate the shaft K in its further rotation feeds the ticket-strip downward, so as to 20 protrude the end thereof through the slot H'. (Shown in Figs. 5 and 7.) The feeding of the strip is effected by the rotation of feed-rolls d¹¹ and d¹², the roll d¹¹ being actuated by 25 its pinion, which meshes with the gear d⁵, which is carried by the yoke d⁶. On the shaft K the projecting segment k⁵ strikes the toothed disk d¹⁰, and thereby turns gear d⁹ against spring d¹⁴, Fig. 10, accurately to mesh 30 with segment-gear k⁶, which moves the yoke d⁶ upward, rocking it upon its pivot, (shown in Fig. 5,) this rocking movement being against the stress of the spring d⁸, which presses against the tail d⁷ of the yoke d⁶. On 35 the back side of the mechanism, as seen in Fig. 4, there is pivoted the bell-crank d¹⁴ d¹⁵, the end d¹⁵ having a pin-and-slot connection with the yoke d⁶ and the end d¹⁴ having a pin-and-slot connection with the strip-detent 40 d¹³. When in its normal position, the yoke d⁶, through the connections of the bell-crank d¹⁴ d¹⁵, holds the strip-detent d¹³ pressed down upon the paper strip, which it reaches through the slot d⁵. This strip-detent is provided so as to prevent retraction of the strip 45 when the strip-holder D is pressed forward against the printing-types. After the strip-detent d¹³ is released the further rotation of the shaft K carries the segmental gear k⁶ into 50 mesh with the gear-wheel d⁹, and the train of gearing rotates the feed-roll d¹¹ and feeds forward the strip, pushing it out from the slot h', the transverse slot in the knife-plate F being held depressed, so as to permit the passage 55 of the said strip. This operation completes the cycle performed by the main shaft K of the machine.

Severing the ticket-strip.—Referring to Fig. 4, the trigger g projects into the ticket-carrier D through the slot g⁵. (Shown in Fig. 8.) The trigger-arm g' is pivoted to the crank-arm of the piece g², which is spring-controlled by the spring g³. This piece g² appears also in Fig. 5 and carries the lug g⁴ in 60 position to operate upon the knife-catch f⁴.

The end of the trigger g is of proper size and depth to enter one of the previously-prepared perforations in the strip e', so that when the railway-car conductor or other operator takes hold of the end of the protruded ticket-strip and draws it out the trigger g, falling into one of the said perforations E³, is carried downward by the strip, and by the turning of the piece g² the lug g⁴ presses the knife-catch out of engagement with the knife-plate F, 75 which under the stress of spring f¹¹ snaps upward and severs the ticket at the proper point.

In order to insure the proper operation of the trigger g, there is arranged the guide-plate M, pivoted at m, as seen in Fig. 4. This guide-plate has a cam-slot in its arm m', said slot being shown at m² embracing the pin m³, which is fixed to the link f⁸. The other arm of the guide-plate M appears at m⁴, 80 where it is bent to form a vertical open-ended trough whereof the sides are m⁵ and m⁶. When the link f⁸ is lifted by the action of shaft K upon bell-crank lever f⁹ f¹⁰, the arm m⁴ of plate M is swung inward toward 85 the strip-carrier D, so that the trigger g, which is provided for the purpose with the laterally-projecting pin g⁵, (see Fig. 7,) said pin g⁵ traveling between the trough edges m⁵ m⁶, is constrained to descend in the proper 90 path and is instantly lifted out of engagement with the strip when the link f⁸ descends in response to the action of spring f¹¹ as the strip is cut by the knife F, the descent of the 95 disk throwing the plate M outward.

The time-stamp.—The time-stamp (shown at L in Fig. 7) may be operated by a time-piece N, inserted in the proper compartment or receptacle in the casing H. Other types, such as shown at L' L², may be provided at 105 will.

I claim—

1. The combination with a strip-holder, a plurality of coin-passages, a corresponding plurality of independent strip-markers, to 110 impress a strip by the act of inserting a coin in one of the coin-passages, a movable member opposite said strip-markers below said apertures, adapted to be moved by a coin inserted through any of the apertures, and connections from said movable member to a latch, to move the same from its normal position, the latch, and mechanism restrained by the latch in its normal position.

2. The combination with a strip-holder, of 115 a coin-passage, a marker, a movable marker-actuator normally projecting into the coin-passage, so as to be displaced by the insertion of a coin and to actuate the marker by such displacement, and an aperture in the strip-holder wherethrough the marker operates on the strip to impress the same, a movable member opposite said strip-markers below 120 said apertures, adapted to be moved by a coin inserted through any of the apertures, 125 130

and connections from said movable member to a latch, to move the same from its normal position, the latch, and mechanism restrained by the latch in its normal position.

- 5 3. The combination with a strip-holder, of a plurality of coin-passages, a corresponding plurality of markers, a movable marker-actuator for each marker, each actuator normally projecting into a coin-passage so as to be displaced by the insertion of a coin and to actuate its appropriate marker by such displacement, a movable member opposite said strip-markers below said apertures, adapted to be moved by a coin inserted through any of the 10 apertures, and connections from said movable member to a latch, to move the same from its normal position, the latch, and mechanism restrained by the latch in its normal position.
- 15 4. The combination with a strip-holder, of a plurality of coin-passages, a corresponding plurality of markers, an aperture in the strip-holder for each marker, a movable marker-actuator for each marker, each actuator normally projecting into a coin-passage so as to be displaced by the insertion of a coin, thereby to move its appropriate marker in an aperture in the strip-holder, a movable member opposite said strip-markers below said apertures, adapted to be moved by a coin inserted through any of the 20 apertures, and connections from said movable member to a latch, to move the same from its normal position, the latch, and mechanism restrained by the latch in its normal position.
- 25 5. The combination with a strip-holder, of a casing, a plurality of coin-entrances in the casing, a corresponding plurality of markers, each provided with a projection normally obstructing a coin-entrance and a marking-point; apertures in the strip-holder to admit the marking-points, and springs to hold the markers yieldingly in and return them to

45 said normal position, the markers movable against said spring in response to the forcible insertion of a coin in one of said entrances, a movable member opposite said strip-markers below said apertures, adapted to be moved by a coin inserted through any of the apertures, and connections from said movable member to a latch, to move the same from its normal position, the latch, and mechanism restrained by the latch in its normal position.

50 6. In a ticket-delivering mechanism, a casing, a shaft within said casing and an actuating-handle exterior thereto, a stop on said shaft, a latch normally in the path of the stop, to restrain the shaft from rotation in one direction, a ratchet-pawl to prevent rotation of the shaft in the other direction, a 55 coin-passage in the casing, a rocker-plate in the path of a coin, connections between the rocker-plate and the latch to move the latter out of the path of the stop by the act of inserting a coin, a finger, carried by the rocker-plate in the path of the stop, to move the rocker-plate to release an inserted coin.

60 7. In a ticket-delivering mechanism, a casing, a shaft within said casing, a coin-70 aperture in the casing, an actuating-handle for the shaft exterior to the casing, said handle normally covering the coin-aperture, and a loose connection between said handle and shaft to permit limited movement of the handle to uncover the aperture, a stop on said shaft, and a latch normally in the path of the stop, and means to move the latch out of the way of the stop by the insertion of a coin through the aperture.

75 Signed by me at Boston, Massachusetts, this 9th day of November, 1905.

HENRY H. CUMMINGS.
